SINGLE PATIENT DIALYSTATE UNIT

Edwin A. Pecker, Los Angeles, Thomas B. Quinn, Pacific Palisades, and Peter P. Klepa, Los Angeles, Calif., assignors to Vernitron Corporation, New York, N.Y., a corporation of New York

Filed Mar. 24, 1969, Ser. No. 16,405

Term of patent 14 years

Int. Cl. D24—02

U.S. Cl. D83—1

FIG. 1

FIG. 1 is a front perspective view of a single patient dialystate unit showing my new design;

FIG. 2 is a front elevational view thereof;

FIG. 3 is a right side elevational view thereof;

FIG. 4 is a top plan view thereof;

FIG. 5 is a bottom plan view thereof; and

FIG. 6 is a left side elevational view thereof.

The rear elevational view, not shown, is substantially plain.

We claim:

The ornamental design for a single patient dialystate unit, substantially as shown and described.
